CLAIM

The ornamental design for an equipment cabinet, substantially as shown and described.

DESCRIPTION

FIG. 1 is a perspective view of an equipment cabinet showing our new design;

FIG. 2 is a top plan view thereof;

FIG. 3 is a front elevational view thereof; and

FIG. 4 is a side elevational view thereof.

The rear of the cabinet is conventionally flat and unornamented.

Fig. 1.

Fig. 2.

FIG.3.

FIG.4.
